UNITED STATES PATENT OFFICE.

WALTER LYTTON, OF CHICAGO, ILLINOIS.

DESIGN FOR A COMBINED RADIO AND PHONOGRAPH CABINET.

Application filed October 2, 1922. Serial No. 3,868. Term of patent 14 years.

To all whom it may concern:

Be it known that I, WALTER LYTTON, a citizen of the United States, residing at Chicago, in the county of Cook and State of Illinois, have invented a new, original, and ornamental Design for a Combined Radio and Phonograph Cabinet, of which the following is a specification, reference being had to the accompanying drawing, forming a part thereof.

Fig. 1 is a perspective view with the cabinet open. As I consider the inside appearance of the cabinet as an ornamental part of the invention; Fig. 2 is a perspective view with the cabinet closed.

I claim:

The ornamental design for a combined radio and phonograph cabinet, as shown.

WALTER LYTTON.
